UNITED STATES PATENT OFFICE.

VEIT FRANZ VON RIED, OF HILDBURGHAUSEN, GERMANY.

FASTENING FOR COLLARS AND NECKTIES.

SPECIFICATION forming part of Letters Patent No. 536,492, dated March 26, 1895.

Application filed September 27, 1894. Serial No. 624,269. (No model.) Patented in Germany November 9, 1893, No. 76,278; in England August 16, 1894, No. 15,630; in France August 29, 1894; in Belgium September 23, 1894, No. 112,078; in Hungary September 23, 1894, No. 1,202, and in Austria October 24, 1894, No. 44/5,611.

To all whom it may concern:

Be it known that I, VEIT FRANZ VON RIED, a subject of the Duke of Saxe-Meiningen, residing at Hildburghausen, in the Duchy of Saxe-Meiningen, German Empire, have invented new and useful Improvements in Fastenings for Collars and Neckties, (for which I have secured Letters Patent in Germany, dated November 9, 1893, No. 76,278; in England, dated August 16, 1894, No. 15,630; in Austria, dated October 24, 1894, No. 44/5,611; in Hungary, dated September 23, 1894, No. 1,202; in Belgium, dated September 23, 1894, No. 112,078, and in France, dated August 29, 1894,) of which the following is a specification.

This invention consists of a device designed to act both as a collar-stud and as a necktie retainer, which will prevent the neck-bands of neckties, bows, cravats, scarfs, and the like, from slipping either up or down at the back of the neck of the wearer.

In the drawings Figures 1, 2, and 3 show a front elevation, a vertical sectional elevation and a plan respectively of my device applied to a shirt and retaining in position a collar and the neckband of a cravat; and Figs. 4, 5, and 6 show views showing the device detached.

The improved combined stud and necktie retainer comprises a disk *a*, which is provided with a shank *c* and with a screw-like portion *b* the purpose of the latter being to enable the disk *a* to be more readily inserted in the stud-holes.

d are two eyes, which are mounted in the shank *c* in such a manner as to be capable of turning therein.

When employing this device, the disk *a* is twisted first through the stud-hole of the collar and then through that of the neck-band *f* of the shirt, which is thus secured to the collar. The eyes *d* being assumed to be in the position shown in Fig. 6, the neckband *h* of the cravat is passed through them. The eyes *d* are then turned back into the position shown in Figs. 1 and 3, so that the neckband *h* is clipped against the collar *g* by the eyes *d* and they themselves do not now project outwardly beyond the shank *c*.

It will be seen, that by means of this device the neckband of the cravat is prevented from slipping either up or down, and that the device at the same time fulfills the function of an ordinary collar-stud.

Having now particularly described and ascertained the nature of said invention and in what manner the same is to be performed, I declare that what I claim is—

As a new article of manufacture, the combined collarbutton and necktie retainer herein described, comprising a disk *a*, shank *c*, and elongated eyes *d* pivotally connected to the head of said shank and adapted to be folded flat in opposite directions, for the purpose specified.

In testimony whereof I have hereunto set my hand and affixed my seal in presence of two subscribing witnesses.

VEIT FRANZ VON RIED. [L. S.]
